UNITED STATES PATENT OFFICE

2,420,473

FEELER CONTROLLED FILLING RE-
PLENISHING MECHANISM

Saint Julian Geddings, West Columbia, S. C.

Application April 11, 1946, Serial No. 661,438

4 Claims. (Cl. 139—243)

1

My invention relates to automatic filling replenishing looms and has particular reference to the mechanism controlled by the filling feeler means for initiating the replenishing operation.

An important object of the invention is to provide means whereby the arm of the weft hammer may have a fine adjustment with respect to the contact part of the filling replenishing mechanism.

A further object of the invention is to provide means whereby the weft hammer arm may be adjusted horizontally and vertically, in a quick and easy manner.

Other objects and advantages of the invention will be apparent during the course of the following description.

In the accompanying drawings forming a part of this application and in which like numerals are employed to designate like parts throughout the same.

Figure 1 is a perspective view of the feeler end of a loom embodying my invention, parts broken away and parts omitted.

Figure 2 is a plan view of the slide and contact part.

Figure 3 is a side elevation of the slide and contact part, viewed from the line 3—3 of Figure 1, parts broken away.

Figure 4 is a transverse section taken on line 4—4 of Figure 3, and,

Figure 5 is an edge elevation of the weft hammer removed, parts in section.

The numeral 1 designates a lay, having a shuttle box 2 at each end thereof, for receiving the shuttle which is actuated in the usual manner. The shuttle receives the usual automatically ejectable bobbin.

The numeral 5 designates a moveable weft hammer including an upstanding arm 6, cooperating with a member 7, in the well known manner. The arm 6 is provided with a laterally offset portion 6', which is wider than the arm 6 and has a flat face 7'. This intermediate portion 6' has a longitudinal slot 7a.

The numeral 8 designates an adjustable arm. This arm is generally vertically arranged and is provided at its top with a head or dog 9, having a jaw 10. The arm 8 is provided near its longitudinal center with an opening 8', pivotally receiving a bolt 12, extending through the longitudinal slot 7a of the intermediate portion 6'. The bolt 12 carries a nut 12'. The arm 8 extends below the bolt 12 to provide a tail 13. This tail is engaged by an adjusting bolt 14, having screw threaded engagement within an apertured bracket or ear

2

15, which is rigidly secured to the weft hammer 5 and preferably formed integral therewith. The bolt 15 carries a lock nut 16.

The replenishing mechanism comprises a horizontal slide or element 17. This slide has a head 18, carrying apertured ears 19, and a contact element 20 is arranged between these apertured ears and is pivotally connected therewith by a pin 21. This contact element has a generally horizontal

10 jaw 22.

When the bobbin has yarn thereon, the jaw 22 is in the lower position out of the path of travel of the jaw 10, and the replenishing mechanism will not be set into action due to the movement 15 of the weft hammer 5. The numeral 23 designates a side slipping feeler element of a filling feeler 24. The side slipping of the feeler element 23 moves a rod 25 longitudinally to the right, Figure 4, and this rod is connected with the 20 contact part 20 and thereby elevates the jaw 22 so that it is arranged in the path of travel of the jaw 10. When this occurs, the movement of the weft hammer will actuate the replenishing mechanism. The spring means shown in Patent 2,009,864 may be employed to releasably hold the 25 jaw 22 in the raised position. The construction of the weft hammer with the intermediate offset portion 6' having the longitudinal slot, the adjustable arm 8, the pivotal mounting 12, and the 30 adjusting screw 14 and associated elements are new. All other parts are identical with those shown and described in Patent 2,009,864.

When it is desired to adjust the arm 8, the nut 12' is loosened. The arm 8 may be vertically adjusted by shifting the bolt in the longitudinal slot of the offset portion 6'. The arm 8 may be horizontally adjusted by turning the same upon the bolt 12. The fine horizontal adjustment of the arm 8 is effected by turning the 40 adjusting bolt 14. The bolt 14 positively holds the arm 8 against turning movement upon the bolt 12 in one direction. By screwing up the nut 12', the arm 8 is clamped to the flat face 7', and its tail will not then move from the bolt 14.

45 It is thus seen that by manipulation of the bolts 12 and 14, the jaw 10 may be accurately adjusted vertically and horizontally with respect to the jaw 22.

It is to be understood that the form of my invention herewith shown and described is to be taken as a preferred example of the same and that various changes in the shape, size, and arrangement of parts may be resorted to without departing from the spirit of my invention or the 50 scope of the subjoined claims.

Having thus described my invention, what I claim is:

1. In an automatic filling replenishing loom, replenishing mechanism including a slide, a contact part moveably mounted upon the slide and having a jaw, a moveable weft hammer, an upstanding adjustable arm provided near its upper end with a dog having a jaw, a pivot element connecting the arm and weft hammer at a point between the ends of the arm, an adjusting bolt carried by the weft hammer and engaging the adjustable arm beneath the pivot, and filler feeling means to move the contact element and shift the jaw of the same into the path of travel of the jaw of the dog.
2. In an automatic filling replenishing loom, a moveable member of replenishing mechanism, a contact part moveably mounted upon the member and having a jaw, a moveable weft hammer, an upstanding adjustable arm provided near its upper end with a dog having a jaw, said arm having an opening near its longitudinal center and a tail extending below the opening, a bolt carried by the weft hammer and extending through the opening in the arm, an apertured ear carried by the weft hammer and arranged near the tail, an adjusting bolt carried by the apertured ear and engaging the tail, and filler feeling means to move the contact part so that its jaw will be arranged in the path of travel of the jaw of the dog.
3. In an automatic filling replenishing loom, a moveable element of replenishing mechanism, a contact part moveably mounted upon the

moveable element and having a jaw, a moveable weft hammer provided with a longitudinal slot, an adjustable arm provided near one end with a dog having a jaw, said arm having an opening near its longitudinal center and a tail, a bolt extending through the longitudinal slot and opening, an apertured ear carried by the weft hammer and arranged near the tail, an adjusting bolt carried by the apertured ear and engaging the tail, and filler feeling means to move the contact part so that its jaw will be arranged in the path of travel of the jaw of the dog.

- 5
  - 10
  - 15
  - 20
  - 25
4. A weft hammer for an automatic filling replenishing loom, said hammer having an intermediate offset portion provided with a wide flat face and a longitudinal slot, an adjustable arm provided at one end with a dog having a jaw and near its longitudinal center with an opening and having a tail, a bolt extending through the slot and opening, a nut carried by the bolt, and an adjusting bolt carried by the hammer and engaging the tail.
